DESIGN FOR A SHOE

Jean W. Barbey, St. Davids, Pa.

Application May 14, 1936, Serial No. 62,637

Term of patent 3½ years

To all whom it may concern:

Be it known that I, Jean W. Barbey, a citizen of Switzerland, residing in St. Davids, county of Delaware, State of Pennsylvania, have invented a new, original, and ornamental Design for a Shoe, of which the following is a specification, reference being had to the accompanying drawing, forming part thereof,

I claim:

The ornamental design for a shoe substantially as shown.

JEAN W. BARBEY.
